UNITED STATES PATENT OFFICE.

WILLIAM THORPE, OF WELLINGTON, NEW ZEALAND.

AUTOMATIC MACHINE FOR DISPLAYING ADVERTISEMENTS, POSTERS, PICTURES, SHOW CARDS, AND THE LIKE.

Application filed August 13, 1925. Serial No. 50,078.

This invention relates to improvements in automatic machines which are adapted to display advertisements, posters, pictures and the like mounted on a revolvable screen, or 5 the machine may be used for any other similar purpose.

The object of the invention is to provide an improved type of machine whereby the display of said advertisements, posters, pictures, show cards and the like, is entirely 10 automatic; and once the machine is set in motion it will display in the course of the revolution of its screen, any desired number of advertisements or the like for a given 15 time, and such time can be varied. Further, when the full range or series of advertisements or the like has been shown, the machine will automatically reverse itself to again display the advertising matter or the like.

20 The invention comprises a frame member in which is mounted a pair of revolvable superimposed rollers upon which a screen is adapted to revolve; the rollers are in engagement with each other through the medium of an endless belt of leather or the like. Motion is imparted to the top roller by means of an electric motor suitably connected to reduction gearing, on the shaft of which are mounted cams actuating movable lever 25 mechanism having mounted thereon apparatus whose parts engage with suitably positioned projecting pins mounted on an endless chain connected to the said top roller. Automatic means for reversing the action of 30 the rollers is provided, and other details of construction are embodied in the invention as will hereinafter be described.

Referring to the drawings accompanying this specification:—

40 Figure 1 is a perspective rear view of the machine.

Figure 2 is a perspective view of the reversing mechanism.

Figure 3 is a perspective view of the slotted 45 sliding member as seen from underneath same, to more clearly indicate its several component parts, and the operation of same.

Figure 4 is a perspective rear view of the reversing rods, the endless chain, the sliding 50 member and its attendant parts; and the automatic trigger mechanism for controlling the forward or reverse movement of the machine.

Figure 5 is a perspective view indicating the motor, reducing gearing, cam member 55 and the pivoted bar,

Figure 6 is a broken perspective view showing the cam operation of the actuating bars.

Figure 7 is a perspective view of the lever mechanism providing for the reversal of the 60 operation.

There is a frame member preferably of iron comprising four upright standards, 1, 1^A, 1^B, 1^C, adapted to be suitably stayed lengthwise and crosswise to form a rigid construction, means, (though not shown), may be provided at the lower end of each standard for securing the frame in position on any desired site. Two superimposed rollers 2 and 3 of any desired diameter according to 70 the size of the machine are provided; these rollers are each keyed to spindles 4 and 5 respectively, which revolve in ball bearings mounted on adjustable bracket members 6 and 7 secured at each end of the frame member. The said rollers 2 and 3 are adapted to have detachably mounted thereon a screen 8 upon which may be positioned suitable advertisements, posters, cards and the like advertising mediums. On one end of the top 75 roller spindle 4 is a sprocket wheel 9 upon which is mounted an endless chain 10 having a suitable number of links and projecting pins 11. The chain 10 is connected to a lower sprocket wheel 12 mounted on a spindle 13 80 retained in a bearing on an adjustable bracket member 14 attached to the main frame, and so positioned that the second sprocket wheel 12 will be in vertical alignment with the first. This construction provides a means for revolving the top roller 2 in conjunction with 85 parts as will be hereinafter described.

The motive power for the machine is supplied by an electric motor 15 of suitable power according to the size of the machine; for instance, it has been calculated that a machine displaying a poster twelve feet by twelve feet would require a quarter horse power motor to drive it. The motor 15 is suitably positioned adjacent the bottom roller 3, and the drive therefrom is by way of belting 16 on to a pulley, and through worm gearing 17, the worm wheel of which is mounted on a spindle 18 suitably retained in bearings. There is a second worm mounted on the opposite end of the said spindle 18 which by means of a worm wheel 19 meshing with said second mentioned worm actuates a spindle 20 to which are keyed cam members 21 and 22 of peculiar construction as indicated in Figures 1 and 5 100 105 110 and 5.

of the drawings, the said cams are adapted to engage with revolvable roller members 23 and 24 mounted on pivoted bars 25, to raise and lower the bars 25 during the revolution of the 5 said cams. The cam 21 operating beneath the roller members to raise the pivoted bars 25, and the cam 22 operating above the roller members to pull the bars 25 down, thereby ensuring a positive action. The roller 24 10 engages the inner surface 22^A of the cam 22 while the extension 23 of the roller 24 engages the outer surface 21^A of the cam 21. The pivoted bar 25 is indicated by dash and dot lines to save obliterating as much as possible 15 that part of the drawing not understood. It will be clear that the part 23 of the roller is disposed between the two members of the pivoted bar 25 while the part 24 of the roller is projected outwardly from the outer surface 20 face of one of the members of the said bar 25.

It will be seen also that the surface 21^A of the cam 21 coming in contact with the roller 23 will in the course of a portion of its revolution lift the pivoted bar 25, while in the continuation of the revolution will synchronize 25 with the cam 22. The path 21^A of the cam 21 being fashioned to conform with the part 22^A of the cam 22, the only difference being the said paths are struck from a common 30 center but at different radii; the path 22 being greater than the path 21^A of the cam 21. The cam if preferred could be made in one, in these circumstances it would be a face one, the groove for the roller path therein, by its 35 inner vertical surface of the groove is capable of raising the pivoted bar 25 while the outer vertical face of the groove being equivalent to the cam 22, is capable of transmitting a downward movement to the pivoted bar 25. 40 The said bars 25 are pivotally mounted at one end on a spindle 26 attached to the frame member preferably adjacent the motor; and the said bars 25 are then continued across the machine and have mounted on the end 25^A 45 vertically disposed links 27 and 27^A on the end 27^B of which (Figure 3) is pivotally mounted a sliding member 28 in the manner shown in Figures 1, 3 and 4 of the accompanying drawings. The said sliding member 28 which is capable of vertical movement only, is retained in position on two guide rods 50 29 and 29^A positioned one on each side of the aforesaid sprocket wheel 12, and the sliding member 28 when mounted thereon embraces 55 the endless chain 10 connecting the two sprocket wheels 9 and 12 before referred to, see Figure 1 of the accompanying drawings.

At suitable intervals on the endless chain 10 there are metal projecting pins 11 previously referred to, a pin of each set being 60 always in alignment on the chain, see Figures 1, 3 and 4 of the drawings.

Suitably housed within the said sliding member 28 are automatic means for engaging 65 with the said projecting pins 11 suitably

positioned on the endless chain 10 so as to revolve the top screen roller 2 in whichever direction it is desired.

The said engaging means consist of spring retained pivotally mounted flaps or triggers 70 31 and 31^A fashioned as indicated in Figure 3 and forming part of a sliding shutter member 32 capable of longitudinal movement in the bottom of member 28. The said flaps or triggers 31 and 31^A have their central portion 75 35 cut out as shown to permit movement of the endless chain 10 therethrough. Pivotally mounted on the inside face 34 of the slotted sliding member 28 is a circular member 35 from which project two arms 36 and 36^A connected by a cross piece 37 on which is slidably retained a coiled spring 38 on the free end of which is a rod 39 the opposite end of which is connected to the bracket member 14 attached to the frame of the machine, this construction being for the purpose of retaining the circular member in its adjusted position. Connected to the inside face of the said circular member 35 is a pivoted link 40, Figure 3, one end 41 of said link 40 being connected to the aforesaid sliding shutter 32 capable of lateral movement in the bottom of the sliding bar member 28, and as before described, the movement of the shutter 32 actuates the spring retained flaps or triggers 31 and 31^A, which as before described are capable of engaging either set of projecting pins 11 suitably positioned on the sprocket chain 10 before referred to.

Mechanism will now be described for controlling the forward and reverse movement of the screen rollers 2 and 3, and for operating the circular member 35 attached to the sliding shutter 32, whereby on the downward movement of the said slotted sliding member 28, the pivotally mounted and spring actuated flap or trigger adjusted for engagement for the time being will automatically engage with a projecting pin 11 suitably positioned on the chain 10 to either revolve 100 the screen in a forward or reverse direction.

There is a worm 42 mounted on the top roller spindle 4 (see Figure 2) the said worm engages with a worm wheel 44 having any desired number of teeth according to the size of the machine. In the sides of the said worm wheel a series of holes 45 are drilled in which pins are inserted, (one of the said pins being indicated by the numerical 46,) the heads thereof project outwards from each 115 side of the said worm wheel 44. One of the other pins when two are used, project outwardly from the other side of the said wheel 44 (not shown in the drawings) for engagement with a lever 50 to trip the circular member 35 to give the screen an upward movement, while the pin 46 is adapted to engage lever 49 on the top hand edge thereof to trip the circular member 35 to give the screen a 120 downward movement. The number of holes 125 130

in the worm wheel will be the capacity of the machine, and if said machine is running at its full capacity the said pins 46 are opposite each other. If on the other hand, the machine is not running at its full capacity, then for the sake of illustration, presuming that forty advertisements are being exposed, the said pins 46 are so adjusted that the screen will automatically reverse on the completion of the forty exposures. The said worm wheel 44 is suitably retained on a spindle 47 mounted in a projecting bracket 48 attached to the frame of the machine. There are levers 49 and 50 suspended vertically from each side of the worm wheel 44 to be pivoted at their top and on the spindle 47 mounted in the said projecting bracket 48. The said levers are pivotally connected as indicated in Figure 2 of the drawings to cross rods 51 and 52 which pass underneath the top roller 2, thence across the machine to be retained in holes 53 and 53^A formed in the cross stay 54. The downward dependent lever 50 is coupled indirectly to the cross rod 52 through the medium of a horizontal extension 50^A of the said lever 50. A rocking arm 50^B is pivotally connected at 50^C to the said horizontal projection 50^A: the said rocking arm is mounted upon the spindle 50^D, the lower end thereof being pivotally coupled to the cross rod 52 and 50^E. A coiled spring 55 is mounted on the free end 52^A of each cross rod 51 and 52; each spring 55 being kept in position by having one end thereof bearing against the inner face 56 of the cross stay 54 and the other end bearing against a washer 57 which is kept in position on the rod 51 or 52 by means of a split pin 58 passing through the said rod. The object of providing the said coiled springs 55 is to ensure a return of the cross rods 51 and 52 to their normal position as indicated in Figures 1 and 2 after either one has operated the reversing mechanism.

Means for keeping a tension on the screen 8 to prevent puckering thereof comprises two grooved belt pulley members 59 and 60 mounted on each end of the two screen roller spindles 4 and 5 the said pulleys 59 and 60 being connected by a drive of any suitable design such as a leather belt 61, which is preferably of circular cross section. Describing the right hand end of the machine (looking at Figure 1), the belt pulley 59 mounted on the top screen roller spindle 4 is smaller in diameter than the pulley 60 mounted on the bottom screen roller spindle 5, and said pulley 59 is V shaped in order to grip the belt as in the manner of driving pulley; and it is a free pulley when the screen 8 is winding on the top roller 2, and a fixed pulley when the screen 8 is unwinding from said roller 2; the change being effected through the medium of spring retained pawls 62 pivotally mounted on the side of the belt pulley 59

engaging a ratchet wheel 63 mounted adjacent to said pulley. The object of having the said pulley 60 larger than the diameter of the pulley 59 is to rotate the lower screen roller when the screen 8 is being wound thereon at a slightly increased peripheral speed over the top roller 2, thus keeping a tension on the screen 8 and avoiding puckering, and the groove of the said pulley 60 being U shaped permits the belt 61 to slip thereon to provide a frictional release and avoid undue strain or over stretching of the said screen. On the other end of the machine i. e. the left hand, with reference to Figure 2, the position of the pulleys above described are reversed, the free pulley and its spring retained pivotally mounted pawl and the wheel ratchet being attached to the lower screen roller spindle, while the U shaped pulley indicated at 59 is keyed to the spindle 4 of the top roller 2. The object of reversing the position of the pulleys is to rotate the top roller at a slightly increased peripheral speed to keep a tension on the screen and prevent puckering thereof when the said screen is being wound on the top roller and to provide frictional release in the event of undue strain being put upon the said screen.

Means are provided for keeping a tension on the pulley belt drive 61, and comprise a bracket member 64 attached to the main frame of the machine at each end thereof in any suitable position. There is a slot 65 cut in the said bracket 64 in which is adjustably mounted a spindle 66 having mounted thereon a grooved pulley 67 the said pulley by reason of the said slot 65 in said bracket 64 being capable of lateral movement towards or away from the belt 61 according to the tension desired to be placed thereon; and in addition, by increasing or reducing the said tension on the said belt drive 61, any slight irregularity in the travel of the screen 8 can be taken up by tightening or slackening the said belt 61 according to the direction of the irregularity. That is to say, if the said screen 8 is over-travelling, the tension on the said belt 61 is eased, while if the reverse action occurs and the irregularity is under-travel, the tension on the said belt 61 is increased.

Means are also provided for keeping the top roller 2 of the machine from spinning when in operation, and comprises a brake band 68 of any suitable material which engages a flange 69 at one end 70 of the top roller 2, the said brake band 68 being held in position thereon under a slight tension by a coiled spring 71; from the free end of which depends a tension rod 72 having a weight 73 on its lower end. When the main pivoted bar 25 is almost down at the bottom of the stroke, the said bar engages with the weight 73 in a manner to put an added tension on the coiled spring 71, thereby causing

the brake band 68 attached thereto to bear on the flange 69 of the top screen roller 2 and check any tendency of it to spin and cause a puckering of the screen 8.

5 The operation of the machine is as follows:—

Assuming that the screen 8 containing the advertisements and the like is on the top roller 2 ready to be displayed, the screen 8 10 is therefore ready to be wound on to the bottom roller 3.

The motor 15 is then set in motion operating the gearing indicated at 17 and 19 in the accompanying drawings in order to reduce 15 the gear ratio and transmit motion to the main operating spindle 20. In the course of the revolution of the said spindle 20 the cam 21 mounted thereon revolves and coming into contact with the revolvable roller 23 mounted 20 on the pivoted bar 25, moves the said pivoted bar in an upward direction. The pivoted bar 25 in its upward movement actuates the vertically disposed link members 27 and 27^A attached to the said bar 25 and in the slow upward movement of the links the slotted sliding member 28 is raised upwardly on its vertical guides 29 and 29^A to the full height allowed by the cam 21. During the said upward movement, one of the pivoted flaps 31 or 30 31^A (see Figure 3) will pass over the projecting pins 11 on the chain 10, it being understood that the said flaps only move downwardly to allow passing over the said pins, the upward movement of the said flaps being stopped by bearing against the under-surface of the slotted member 28. The cam 21 is now at the height of its travel, and on turning further causes a downward movement of the pivoted bar 25 which downward movement is assisted by the inner face of the 40 second cam 22 engaging the second roller member 24 attached to the pivoted bar 25 during the revolution of the main operating spindle 20.

45 The downward movement of the pivoted bar 25 causes the links 27 and 27^A and the sliding member 28 attached thereto to move downward also, and it is on said downward movement that the projecting pivotal flap 31 as indicated in Figure 3 of the drawings 50 will engage with a projecting pin 11 on the sprocket chain 10, causing the top screen roller 2 and screen 8 attached thereto to be revolved, and thereby bring the advertisement or the like mounted on said screen 8 55 into the display position for a stated time. It will be understood from this description that in the course of their further revolution, the cams 21 and 22 will operate the pivoted bar 25 and its attendant parts to repeat 60 the display operation, and also that upon the downward movement of the pivoted bar 25 a tension is placed on the coiled spring 71 with its brake band attached thereto, to check any 65 tendency of the screen roller to spin.

Describing the operation of the various parts for reversing the action of the machine, that is, when it is desired to revolve the screen containing the advertisements from the bottom roller 3 on to the top one 2. During the 70 course of the revolution of the top roller 2 in the forward direction, it actuates the worm 42 attached to the top roller spindle 4 and in its revolution the worm 42 revolves the worm wheel 44 before referred to. Pins 46 75 have been placed in the holes 45 in the face of the pinion 44 at desired intervals, and during the course of the revolution of the pinion, the pin on the inside face of said pinion will engage with its dependent lever 49 and cause such dependent lever 49 and cross rod 51 attached thereto to be moved forward against the influence of its spring 55 so that the point 51^A of the lever 51 projects through the hole in the cross stay 54, and on the next upward movement of the slotted sliding member 28, the arm 36 connected to the circular member 35 will engage with the protruding point 51^A of the lever 51 causing said arm 36 to be forced downwards turning the circular member 35 on its spindle, and in its revolution actuating the link 40 connected to the sliding shutter 32 which will cause the forward flap or trigger 31 to be thrown out of gear with the pin 11 on the sprocket chain 10 and the reverse trigger 31^A to be automatically drawn into a position to engage the opposing pin 11 on the sprocket chain 10, and so revolve the top roller 2 in the reverse direction on the next downward movement of the slotted sliding member 28. It will be understood from this description when the bottom screen roller 3 has been again unwound, that the reversing gear before referred to will operate the lever 50 and its cross rods 52 causing the circular member 35 to be returned to the position as is indicated in Figures 3 and 4 of the accompanying drawings.

The mechanism of the machine is adapted to be suitably enclosed in a casing member made of any desired material such as wood, and will have a glass front, in which will be a defined space for the advertisement and the like matter to appear before the public vision.

From the foregoing description it will be apparent that there is thus provided a device of the character described possessing the particular features of advantage before enumerated as desirable, but which obviously is susceptible of modification in its form, proportion, detail construction or arrangement of parts, without departing from the principle involved or sacrificing any of its advantages.

What I claim as new and desire to secure by Letters Patent is:—

1. An improved automatic machine for displaying posters, pictures, show cards, and the like, comprising a frame member, a pair of 130

revoluble superimposed rollers mounted thereon, a driving connection between the rollers, a screen containing advertisements and the like mounted on said rollers, a motor, 5 a drive chain connected to the upper roller but free of driving connection with the lower roller, a sliding member to embrace said chain, pins on the chain, means on the sliding member whereby the pins may be selectively

10 engaged to move the same in either direction in the movement of the sliding member, links depending from the sliding member, bars pivotally supported at one end and connected at the opposite end to said links, and cam mechanism 15 for operating the bars in both directions whereby to reciprocate the sliding member.

2. An improved automatic machine for displaying posters, pictures, show cards, and the like, comprising a frame member, a pair of revoluble superimposed rollers mounted in spaced vertical alignment thereon, a driving connection between the rollers, a screen containing advertisements and the like 20 mounted on said rollers, a drive chain connected to but one roller, a sliding member to embrace said chain, pins on the chain, pin engaging elements carried by the sliding member, means for operating said pin engaging 25 elements to selectively engage the pins on either length of the chain to operate the latter in one direction or the other, bars pivoted at one end to the frame and extended beneath the lowermost roller, links connecting the free 30 ends of said bars with the sliding member, cam mechanism supported on the frame beneath the lowermost roller for operating the bars in both directions whereby to reciprocate the sliding member, and a motor carried by 35 the frame for operating the cam mechanism.

3. An improved automatic machine for displaying posters, pictures, show cards and the like, comprising a frame member, a pair of revoluble superimposed rollers mounted 40 thereon, an advertisement carrying screen mounted on the rollers, means for imparting motion to the top roller to cause the advertisements on the screen to be displayed for a determinate period, said means including a drive chain connected to the upper roller, a sliding member to embrace the chain, pins on the chain, and means on the sliding member

to automatically engage either set of pins, said means comprising a sliding shutter member mounted in the bottom of the said sliding member and having flaps pivotally mounted on the said sliding member. 55

4. An improved automatic means for displaying posters, including an upper and a lower roller, a display screen wound on the rollers, a drive chain for the upper roller, an operating means for said chain including pins carried on the chain, a member reciprocated longitudinally of the chain, selectively operable means carried by the reciprocated member whereby the pins may be engaged to move the chain in one direction or the other, and mechanism for automatically controlling the action of the selectively operable means including a wheel operated in the movement of the upper roller, a link controlling said selectively operable means, said wheel being formed with a series of openings to selectively receive a pin adapted to engage and operate the link at a predetermined point in the movement of the wheel, and means operated by the link to be moved to a position to control the action of said selectively operable means to thereby shift the selectively operable means for reversing the operation of the chain. 70

5. An improved automatic machine for displaying posters, pictures, show cards and the like, comprising a frame member, a pair of revoluble superimposed rollers mounted thereon, a screen containing advertisements or the like mounted on said rollers, means for imparting motion to the top roller for causing the advertisements on the screen to be displayed for a stated period, means for automatically reversing the action of the rollers, 80 and means for keeping the tension on the screen to prevent puckering thereof, said last named means comprising pulleys arranged in pairs, one roller of each pair being fixed to a particular screen roller spindle and the other roller of each pair having connection with the other screen roller spindle to fix the roller thereto or free the roller therefrom in accordance with the direction of rotation of the spindle, a driving belt connecting each pair of pulleys, and an adjustable pulley to provide a varying tension for the said driving belt. 95

In testimony whereof I affix my signature.
WILLIAM THORPE.
